UNITED STATES PATENT OFFICE.

WILLIAM SCHMID, OF COLDWATER, MICHIGAN, ASSIGNOR TO CASKEY-DUPREE MANUFACTURING COMPANY, OF COLDWATER, MICHIGAN, A CORPORATION OF OHIO.

OBJECT-INCLOSING CASING.

Application filed April 5, 1926. Serial No. 99,939.

My invention relates to objects inclosing casings having closures and resides in the provision of improved interengaging formations upon the body of such a casing and the closure therefor whereby the closure may be surrounded by the casing body.

In accordance with my invention, the closure is provided with tongues projecting from the edge thereof into recesses formed 10 in the casing body and the casing body, in turn, is formed with tongues that project into recesses formed in the closure. Each tongue upon the closure also constitutes a wall of one of the recesses, the tongues and 15 recesses upon the closure being distributed in couples around the closure. The tongues and recesses upon the body of the casing are similarly inter-related. The interengaging formations upon the casing body and casing 20 closure are thus provided in compact arrangement without weakening the structure.

The casing of my invention is of particular service in the construction of switches having 25 movable switching parts within the casing and terminal contacts passing through the casing closure where they are connected with the circuit wires. The recesses in the casing closure receive the tongues upon the casing body at a depth which will widely space 30 tongues upon the casing body from the circuit wires upon the outer face of the closure whereby the casing body, which is customarily metallic, is removed from the short circuiting relation with the terminal contacts upon the casing closure.

The accompanying drawing illustrates 40 the preferred embodiment of the invention as employed with a switch structure, Fig. 1 being a rear view of a switch having a casing of my invention; Fig. 2 is a sectional plan view on line 2—2 of Fig. 1; Fig. 3 is a plan view of part of the casing; and Fig. 4 illustrates a portion of the casing body and casing closure in perspective and in separated 45 relation.

The structure illustrated includes a metallic cylindrical casing body 1 having a wall 2 at one end thereof. This casing body is 50 suitably assembled at its said end wall with a mounting plate 3. The said end wall is inwardly dished to provide, with the mounting plate, an annular recess 4. The hub portion 5 of a switch handle 6 is formed with flanges 7 that are received in the recess 4, 55 the inner end of the hub projecting through

a circular hole 8 in the mounting plate, this hole being coaxial with the casing body. This construction and arrangement of the handle permits it to be turned upon the axis of the casing body. A ring 9 of insulation is also coaxial with the casing body, the handle being placed in turning engagement with this ring by means of the tongues 10 that are received within grooves 11 formed upon the inner side of the ring. This ring 60 is formed with cylindrical recesses 12 in which the cylindrical spring barrels 13 are slidably received. These spring barrels house coiled springs 14 and inclose the headed ends of the plungers 15 that project 65 through the spring barrels into engagement with the end walls of the recesses 12. The springs 14 press upon the plungers and also upon the spring barrels and therefore tend to press these parts in opposite directions. 70 The spring barrels are mounted upon a floating contact carrier 16, here shown as a metallic ring. The ends of the spring barrels opposite the ends through which the plungers project constitute contacts which are 75 engageable with the contacts 17 which are in the nature of flanges at the inner ends of metallic bushings 18. These metallic bushings are also provided with flanges 19 at their rear ends. The metallic contact bushings 18 are 80 carried by and passed through a closure in the form of a circular plate 20 formed of insulating material. The bushings are threaded to receive binding screws 21 that clamp the circuit wires 22 into firm mechanical and 85 electrical engagement with the bushings.

The closure 20 is surrounded by the casing body and has tongues 23 in the plane thereof that project beyond the closure 20 into recesses 24 formed in the casing body. 90 The casing body is formed with tongues 25 that are inwardly bent at angles to the cylindrical wall of the casing body to be received within recesses 26 formed in the closure. The tongues 23 are of the full thickness of the circular closure 20, while the recesses 26 are of a depth less than the thickness of the closure to afford slots for the angular tongues 25. The angular tongues 25 upon the casing body 95 firmly hold the closure tongues 23 in the bottoms of the recesses 24 whereby the contacts 17 are held in a fixed plane to enable the contacts upon the carrier 16 to be properly brought into and out of engagement therewith. The recesses 26 in the closure define 100 105 110

positions for the inturned tongues 25 which will widely separate these tongues from the bushing flanges 19 and the wires clamped against these flanges by the screws 21 whereby the tongues 25 are prevented from having short circuiting relation with the contacts upon the closure. The tongues 23 constitute walls of the recesses 26, each tongue 23 thus having a recess 26 immediately contiguous thereto, the recesses 24 and tongues 25 in the casing body being similarly related.

Having thus described my invention, I claim:

A casing structure comprising a cylindrical casing body and a closure in the form of a circular plate surrounded by the casing body, said casing body and closure being each formed with immediately contiguous tongues

and recesses, the tongues upon the closure being in the plane of the closure and substantially of the thickness of the closure, the recesses in the closure being less in depth than the thickness of the closure to afford seats for the tongues upon the casing body, these tongues being inwardly bent into the recesses in the closure and engaging the aforesaid slots to hold the closure against outward movement with respect to the casing, the tongues upon the closure projecting into the recesses in the casing body and acting independently of the tongues on said casing to hold the closure against turning movement within the casing.

In witness whereof, I hereunto subscribe my name.

WILLIAM SCHMID.
